UNITED STATES PATENT OFFICE

WILLIAM A. NEWMAN, OF MONTREAL, QUEBEC, CANADA, ASSIGNOR TO UNIVERSAL DRAFT GEAR ATTACHMENT COMPANY, OF CHICAGO, ILLINOIS, A CORPORATION OF ILLINOIS

RAILWAY BRAKE

Application filed April 22, 1931. Serial No. 531,896.

This invention relates to brakes for railway cars and more particularly to the drop staff type of brake.

One of the objects of the invention is the provision of new and improved means for holding a telescopic or drop brake staff in elevated position.

Another object of the invention is the provision of a new and improved brake staff holding device with novel means for disconnecting the holding means from the staff when it is desired to lower the same.

A further object of the invention is the provision of new and improved brake staff holding device that is located in an accessible position for manipulation by the operator.

Another object of the invention is the provision of a new and improved drop brake mechanism that is inexpensive to manufacture, easily assembled, efficient in operation, conveniently located, and that is not likely to become broken or get out of order.

Other and further objects and advantages of the invention will appear from the following description taken in connection with the accompanying drawing, in which

Fig. 1 is a vertical section of a portion of an end of a car, showing the invention in position thereon;

Fig. 2 is a section on line 2—2 of Fig. 1;

Fig. 3 is a vertical section of a portion of the device, showing the brake staff in elevated or operative position.

Fig. 4 is a similar view to that shown in Fig. 3, but at right angles thereto;

Fig. 5 is a section on line 5—5 of Fig. 4; and

Fig. 6 is a view similar to Fig. 3, but showing the brake staff in lowered position.

Referring now to the drawing, the reference character 10 indicates generally the end of a car having the end sill 11. The floor 12 of the car is provided at its outer end with a recess 13 for receiving the brake wheel 14 when the same is in lowered position.

The brake mast, designated generally by the reference character 15, comprises a lower section or winding member 16 which, in the construction shown, is in the form of a sleeve terminating at its lower end in the winding

drum 17, and an upper section or brake staff 18 on the upper end of which is secured the brake wheel 14. The brake staff 18 is slideable through the winding member 16 for raising and lowering the brake wheel 14 as will presently appear.

The winding member 16 is reduced at its lower end and is journaled in the brake mast step 19 which in turn is secured to the end sill 11 as is usual in such constructions. The brake mast step 19 may be of any well known construction, and since the details of the same constitute no part of the present invention it is not thought necessary to further illustrate or describe the same. It is provided at its upper end with the outwardly extending flange or bracket 21 within which the upper end of the winding member 16 rotates.

The brake staff 18 is angular in cross-section for engaging a corresponding angular opening in the winding member 16 for rotating the same when the brake wheel is rotated for applying the brakes. Suitable mechanism is provided for holding the brakes applied when the brake wheel 14 is rotated. As shown, this comprises a ratchet wheel 22 having the ratchet teeth 23 on its under side which are adapted to be engaged by a pawl 24. A pivoted weight member 25 is so mounted that when it is turned to one position it will engage the tail 26 of the pawl 24 for holding the inner end of the pawl against the teeth 23 and when turned to the other position it will hold the pawl out of engagement with said teeth. This structure is well known in the art and need not be further described.

Suitable means are provided for holding the brake staff 18 in elevated position. This means is so constructed that when the staff is elevated above the same it will be moved by gravity into the path of the staff for engaging the lower end thereof for holding the same in its operative position.

It is common practice in what is known as the drop staff type of brake to provide means at the lower end of the winding member for holding the staff in elevated position. But this arrangement is objectionable be-

cause of the inconvenience in releasing the latch or holding mechanism when it is desired to lower the brake staff. It has also been proposed to provide the upper portion 5 of the winding member with a latch or holding means for maintaining the staff in elevated position, but such means is provided with but a single handle for releasing the same, and such an arrangement is objectionable because the latching means, being mounted on the winding member, will at times be rotated to a position that will be inconvenient if not inaccessible to the operator.

10 15 The present invention seeks to eliminate these defects by the provision of a holding element located on the upper portion of the winding member and provided with a plurality of elements for operating the same. 20 25 These elements are angularly spaced about the winding member so that in whatever position the brake staff may be secured at least one of these operating elements will be readily accessible for releasing the holding element.

In the form of construction selected to illustrate one embodiment of the invention the bail or holding element or member 27 is in the form of the letter U, having outwardly 30 35 extending trunnions 28 and 29 on its upper end. These trunnions are journaled in the upper end 31 of the winding member 16.

The upper end 31 of the winding member is distorted laterally as at 32 to form a recess 33 for receiving the holding element 27 when the same is moved to inoperative position. Handle members 34 and 35 are provided for operating the holding element 27. These handle members may be secured in any 40 45 suitable manner to the holding element. As shown, they are cast integral with the trunnions 28 and 29 and are so constructed that their center of gravity will be at one side of the plane of the bail or holding element 27. By means of this arrangement the weight of the holding element and that of the handles 34 and 35 will be such as to cause the holding element to move by gravity 50 55 into the path of the brake staff 18 when the same is elevated above said element. The lower end of the brake staff may be and preferably is provided with a recess 36 which in the form shown is concave for engaging the horizontal portion 37 of the holding element 27.

Suitable means are provided for permitting the holding element to be assembled in position on the winding member. Any suitable means may be employed for this 60 purpose. As shown, which is by way of example only, the upper end of the winding member is slotted as at 38 which will permit the holding element to be inserted from the top through the slot 38. Suitable means 65 are also provided for holding the bail 27

in its assembled position. In the form of construction shown, the upper end of the winding member is provided with lugs or projections 39 extending outwardly therefrom.

70 A cap 41 having an annular recess 40 in its inner wall for receiving the lugs 39 is provided for preventing removal of the bail. This cap is provided with longitudinally 75 extending slots 42 on its inner surface through which the lugs 39 are inserted for securing the cap in position.

In assembling the parts, the holding element 27 is inserted through the slot 38 in the upper end of the winding member, after which the cap is applied by causing the lugs 39 to engage the slots 42 and then rotating the cap, after it is lowered in position, to cause the lugs to engage beneath the shoulders formed by the recess 40 for preventing the removal of the cap. The cap 41 has an angular opening through its top wall for receiving the staff which, when the parts are assembled, will prevent the rotation of the cap relative to the winding member 16. This cap extends through an opening 43 in the flange or bracket 21 and may be said to form the upper journal for the brake mast.

80 85 Assuming that the parts are in the position shown in Fig. 1, and it is desired to operate the brake, the brake staff 18 is elevated above the horizontal portion 37 of the holding member 27 whereupon the latter will fall by gravity into the path of the brake staff. The brake staff is now lowered to cause the holding element to engage in the recess 36. This recess will prevent the accidental disengagement of the holding member from the brake staff.

90 100 105 When it is desired to lower the staff, one of the handle members 34, 35 is moved in a direction to cause the holding member to enter the recess 33. The horizontal portion 37 of the holding member is curved on its upper surface for engaging the concave recess 36, whereby, when the handle member 34 or 35 is moved outwardly, it will cause the horizontal member 37 to ride out of the recess 36 for releasing the brake staff. The staff may then be lowered with the wheel 14 occupying a position within the recess 13 of the floor 12.

110 I claim as my invention:

115 1. In a railway brake operating mechanism, a brake mast comprising a lower section, an upper section rotatable with said lower section and slidably mounted therein, a holding member normally positioned by gravity in the path of movement of said upper member, and means at opposite sides of said staff for moving said member out of the path of movement of said upper section.

120 125 130 2. In a brake operating mechanism, a winding member, a vertically movable brake staff for operating said member, a gravity op-

- erated holding element for engaging said staff for holding the same in elevated position, and a plurality of means angularly spaced about said winding member for moving said holding element out of engagement with said winding member preparatory to lowering said staff.
3. In a railway brake operating mechanism, a winding member, a pawl and ratchet for holding said winding member in brake applying position, a vertically movable brake staff for rotating said member, said staff being movable vertically and having a concave recess on its lower end, a U-shaped holding member journaled in the upper portion of said winding member and movable by gravity to a position beneath said recess and in the path of said staff when the latter is elevated above said holding means for limiting the downward movement of said staff.
4. In a device of the class described, a sleeve member having a winding drum on its lower end, a brake shaft step for supporting said sleeve member, a brake staff telescopically mounted in said sleeve member, a U-shaped holding member journaled in the upper portion of said sleeve member, and a weighted handle element for normally holding said holding member in the path of said staff.
5. In a brake operating mechanism, a brake shaft step, a sleeve member journaled in said step, a vertically movable brake staff for operating said sleeve, a U-shaped holding member journaled in said sleeve for holding said staff in elevated position, and weighted handle members connected to said holding member and adapted to normally hold said last-named member by gravity in the path of said staff.
6. In a brake operating mechanism, a winding member, a brake staff for rotating said member, a U-shaped holding member journaled in said winding member, a handle member secured to said holding member for moving the same to inoperative position, said handle member being so mounted that its weight will tend to maintain said holding member in the path of said staff.
7. In a brake winding mechanism, a winding member, a brake staff vertically slideable in said member, said staff having a recess in its lower end, a U-shaped holding member journaled in said winding member, said winding member having a recess in one side thereof, a handle attached to each end of said holding member for moving the same out of the path of said staff into said recess, the center of gravity of said handle member being outwardly of the plane of said holding member whereby when said staff is elevated above said holding member the latter will move by gravity beneath said staff for engaging said first-named recess when said staff is lowered.
8. In a brake operating mechanism, a brake shaft comprising an upper section and a lower section, the upper section being slideable within the lower, a gravity operated latch member cooperating with said upper section for holding the same in elevated position, and means at opposite sides of said lower section for operating said latch member.
9. In a brake operating mechanism, a brake mast comprising a sleeve member having vertical slots in its upper end and provided with a recess in its wall spaced 90 degrees from said slots, a U-shaped holding member having laterally extending trunnions for engaging in said slots, handle members carried by said trunnions for rotating said holding member into said recess, a cap for holding said trunnions within said slots, means for preventing the removal of said cap from said sleeve member and a brake staff slidably mounted in angular openings in said cap and sleeve member for causing the same to rotate together when said staff is rotated.
10. A holding member for a railway drop brake mechanism comprising a U-shaped brake staff supporting element, said element terminating in oppositely directed trunnions and handle members carried by said trunnions, said handle members being arranged to extend in a plane at an angle to the plane of the U-shaped portion of said element.
11. In a railway brake operating mechanism, a sleeve member having its lower end terminating in a winding drum and having its upper end provided with oppositely arranged slots extending longitudinally of said member and having lugs extending radially outwardly from its upper end.
- In testimony whereof I affix my signature.
